5 Sheets-Sheet 5

<img alt="A detailed technical cross-sectional diagram of a mechanical assembly, likely a cylinder or pump, featuring various components labeled with numbers 92 through 141. The diagram shows a central vertical rod 132, a piston 133, and a connecting rod 131. The assembly is supported by bearings 136 and 137, which are mounted on a housing 138. The base of the assembly includes a valve 78, a piston rod 115, and a piston 114. A flywheel 100 is attached to the bottom, and a flywheel housing 99 is shown. Various other parts like 101, 102, 103, 104, 105, 106, 107, 108, 109, 110, 111, 112, 113, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, Harry Block,
ATTORNEY.

UNITED STATES PATENT OFFICE

2,420,983

METHOD OF AND MACHINE FOR
PACKAGINGLeroy L. Salfisberg, South Orange, N. J., assignor
to Ivers-Lee Company, Newark, N. J., a corpora-
tion of Delaware

Application May 12, 1945, Serial No. 593,429

15 Claims. (Cl. 93—3)

1

This invention relates in general to the art of packaging, particularly the packaging of fluent materials, such as pastes, namely, cold creams and suppositories, or liquids, namely, oils and hand lotions, or powder, and more specifically the invention contemplates a package of the type which includes opposed layers of relatively thin packaging material sealed together in certain zones which form the boundaries of a compartment or chamber between said layers to receive the material being packaged.

One object of the invention is to provide a novel and improved method of making a package which shall be of said general character but shall have a compartment or chamber of irregular shape or of widely varying cross-sectional area at different points, for example of the shape of a suppository.

Another object is to provide a package of the general character described which shall include novel and improved features of construction such that all air shall be excluded from said chamber or compartment, the package shall be tightly sealed against leakage of the contents and at the same time the walls of the package may yield or expand to compensate for pressure on the walls of the chamber during filling of the chamber or during handling of the package or as the result expansion of the packaged material under heat, so as to reduce the possibility of rupturing of the package walls or weakening of the sealed zones.

Still another object is to provide such a package that shall include novel and improved features of construction whereby the package can be easily opened for removal of the packaged material.

Another object is to provide a machine for packaging fluent material and embodying novel and improved features of construction for forming a tube of opposed strips of ductile material, depositing in the tube fluent material to be packaged and transversely pressing together the walls of the tube at zones spaced longitudinally of the tube so as to form and bound compartments of predetermined shape and volume each completely filled with the material being packaged, and sealing said strips together in areas surrounding said pressed zones.

A further object is to provide a machine of this character which shall include compensating means for pressing the layers of packaging material to form the chamber for the material being packaged and to prevent wrinkling at the edges of the formed chamber to reduce the pos-

2

sibility of tearing of the package layers during formation of the chamber and during handling of the package, as well as under expansion of the packaged material under heat.

- 5 Still another object is the provision of a practical machine for feeding strips of ductile material, crimping the material and automatically attaching the strips together along the predetermined line or lines.
- 10 Other objects and advantages of the invention will be apparent from the description thereof to follow taken in conjunction with the accompanying drawings in which—

Figure 1 is an elevational sectional view of a machine embodying one form of the invention.

Figure 2 is a vertical sectional view taken on the plane of the line 2—2 of Figure 1, parts being broken away.

Figure 3 is an enlarged fragmentary detail view of the die rollers.

Figure 4 is a detail view showing the development of the packages in chain formation in accordance with the invention.

Figure 5 is an enlarged plan view of one form 25 of package made in accordance with the invention.

Figure 6 is a sectional view taken on the plane of the line 6—6 of Figure 5.

Figure 7 is a sectional view taken on the plane 30 of the line 7—7 of Figure 5.

Figure 8 is an enlarged plan view of another modified form of package made in accordance with the invention.

Figure 9 is a sectional view taken on the plane 35 of the line 9—9 of Figure 8.

Figure 10 is a sectional view taken on the plane of the line 10—10 of Figure 8.

Figure 11 is an enlarged plan view of still another modified form of package made in accordance 40 with the present invention.

Figure 12 is a longitudinal sectional view of a machine embodying a modified form of the invention.

Figure 13 is a sectional view taken on the plane 45 of the line 13—13 of Figure 12.

Figure 14 is a sectional view taken on the plane of the line 14—14 of Figure 13.

Figure 15 is a detail view showing the development 50 of packages in chain formation made in accordance with the form of the invention shown in Figure 12.

Figure 16 is an enlarged plan view of a package made in accordance with the form of the 55 invention shown in Figure 12.

Figure 17 is a sectional view taken on the plane of the line 17—17 of Figure 16.

Figure 18 is a sectional view taken on the plane of the line 18—18 of Figure 16.

Referring to the particular form of the invention shown in Figures 1 and 2 of the drawings, rolls 1 and 2 of ductile packaging material are rotatably supported on the frame 3 of the machine. The material is preferably coated metal foil but it may be any other suitable packaging material such as transparent thermoplastic coated Cellophane and the like. The rolls 1 and 2 supply ribbons or webs 4 and 5, respectively, of material which are led upwardly over introductory idler pulleys or rollers 6 and 7, respectively, disposed on opposite sides of inlet and outlet pipes or tubes 8 and 9, respectively, which lead to a liquid reservoir (not shown).

After passing over the rollers 6 and 7, the ribbons 4 and 5 are fed upon opposite sides of the ends of the pipes 8 and 9 so as to pass between longitudinal edge-sealing rollers 10 and 11. The roller 10 is mounted on a shaft 12 extending from the machine frame and roller 11 is mounted on a bearing member 13 pivotally mounted on a shaft 14 supported on the frame, said bearing member having a downwardly projecting extension 15. The rollers 10 and 11 have peripheral crimping portions or spaces 16 adjacent opposite ends thereof as may be seen in Figure 2. As shown in Figure 1, these edge-sealing and crimping portions on both rollers mutually engage to forcibly interdigitate the edges of the ribbons 4 and 5 as indicated at 17. These crimping rollers are provided with internal electrical heating elements for applying heat in sufficient quantities to fuse the thermoplastic coatings on the ribbons 4 and 5 and provide a complete fluid seal. This sealing of the edges of the ribbons converts said ribbons into a tubular package structure surrounding the pipe 8 and 9, the tubular structure being directed between further crimping, scoring, shaping and severing devices.

Means are provided for transversely sealing and scoring the tubular structure at spaced intervals. Such means includes a pair of sealing and scoring rollers 18 and 19. Roller 18 is mounted on a shaft 20 extending from the machine frame and roller 19 is mounted on a bearing member 21 pivotally mounted on a shaft 22 supported on the frame. Bearing member 21 is provided with an integral extension 23 projecting upwardly. Rollers 18 and 19 have spaced peripheral crimping portions or spaces 24 and 25 for mutual complementary mechanical engagement as the rollers are rotated in opposite directions. Interposed between said crimped surfaces 24 and 25 are knives 26. The rollers are provided with internal electrical heating elements for applying heat in sufficient quantities to fuse the coatings on the ribbons 4 and 5. When the crimped portions are mutually engaged as shown in Figure 1, the tubular structure is pressed together and the opposed walls thereof are forcibly interdigitated by virtue of the crimped deformations as indicated at 27 and 28 in Figure 4, and at the same time the material is scored transversely by the knives as indicated at 29 and the thermoplastic material on the walls of the tubular structure is fused so as to form a complete fluid tight transverse seal which, with the edge seals, provides a rectangular shaped package 30.

From the rollers 18 and 19, the webs advance between a pair of dies in the form of rollers 31 and 32. Roller 31 is fastened to a shaft 33 sup-

ported on the frame and roller 32 is supported by a bearing member 34 which is pivotally mounted on a shaft 35 extending from the frame and which has an upwardly projecting extension 36. The rollers 31 and 32 are formed with a series of peripheral spaced transverse semi-circular grooved portions 37 between their end walls 38. Floatingly and rockingly mounted in the grooves 37 are semi-circular shaped die members 39, said die members being provided with stub shafts 40 at their ends adapted to slidably fit in curved slots 41 formed in the faces of the end walls 38. The die members are formed with longitudinally disposed grooves 42 in their flat-faced portions 39, said grooves being substantially semi-circular in cross section and having tapered walls. The flat-faced portions have crimping surfaces or spaces for mutual complementary mechanical engagement as the rollers are rotated. Upon rotation of the rollers 31 and 32 in opposite directions, the die members 39 swing and rock bodily in the grooves, the slot and shaft connections permitting this movement, but upon coming into engagement with each other said die members automatically adjust themselves bodily so that the face portions thereof meet and engage whereby the opposed walls of the tubular structure are pressed together over the entire surface thereof except opposite the groove portions 42. At the same time, the material is gathered longitudinally and transversely of the webs above and below the grooved portions as indicated at 43 to form central elongated compartments or chambers 44 into which the fluid is forced by the compression of the walls. The transverse scoring permits the webs 4 and 5 to be torn so as to insure adequate free material to form the compartments and to compensate for said gathering of the material along the boundaries of the compartments, and thereby prevent rupturing of the material in the package walls.

The rollers 10 and 11, 18 and 19 and 31 and 32 may be provided with means for effecting fine adjustments of their relative positions and for regulating the pressure of the rollers upon the material. As shown in Figure 1, a bracket member 45 is cast on the frame and is vertically disposed between the bearing members 13 and 21 for the rollers 11 and 19 so that it overlaps the extensions 15 and 23. At its upper end, the bracket is split and supports an adjusting screw bolt 47 adapted to engage the extension 15 for adjusting the roller 11 toward and from the roller 10, a cap screw 46 being provided to clamp the screw 47 in adjusted position.

Roller 19 is adjustably spring pressed toward the roller 18 by means of a screw bolt 48 passing loosely through the extension 23 and engaging screw threads on the bracket 45 and held in adjusted position by a cap screw 46a, and a spring 48a interposed between the extension and the bracket.

Roller 32 is adjusted toward and from the roller 31 by a screw bolt 50 supported by a bracket member 51 fastened to the frame and which bolt is adapted to engage the extension 36.

At the bottom of the line of travel of the tube structure, severing mechanism is provided for cutting off the formed packages in single units. This severing mechanism comprises a pair of rollers 52 and 53 provided with spaced grooved portions 54 to receive the formed compartment 44 and with radial slots 55 between said grooved portions. The radial slots 55 in roller 53 seat blades 56 enclosed in rubber sleeves 57 with their

edges protruding slightly beyond the periphery of the roller. The rollers 52 and 53 are mounted on shafts 58 and 59, respectively, extending from the machine frame and upon rotation of the rollers, the material, at the joints between the rollers, the material, at the joints between the formed packages, along the scoring lines of the unseparated portions, is pressed by the rubber covered blades into the slots 55 in roller 52 and stretched to the breaking point, the severed package falling into a hopper or the like not shown.

The rollers 10 and 11, 18 and 19, 31 and 32 and 52 and 53 are mechanically intergeared and driven by a shaft (not shown) in timed relationship.

Any suitable arrangement may be utilized for ejecting liquid or fluid into the tubular packaging structure, for example, a forcing injection pump system may be used for injecting a measured quantity of fluid into and through the tube 8 at a predetermined time. Again where the fluid constitutes a finely divided substance such as powder, the pipes 8 and 9 can be connected with a powder containing chamber having a measuring cavity and a release closure therefor, the release closure being operated at timed intervals by a cam driven in timed relation with the other movable parts of the mechanism so that each formed package is filled with the powder prior to its closure.

In the operation of the system, the fluid from the reservoir is fed through and down pipe 8 into the tubular structure formed by the ribbons 4 and 5 longitudinally sealed together along their edges by rollers 10 and 11. The fluid fed into the tubular structure produces a standing column of fluid of a level determined by the level of the fluid in the reservoir. The transverse sealing rollers 18 and 19 operate to act through the standing column of fluid and permanently heat seal together the tubular structure in spaced areas to provide individual fluid containing package units joined together in chain package formation. The die rollers 31 and 32 press the walls of the material together under cold pressure and shape the chambers 44 by gathering the material longitudinally of the webs and simultaneously forcing the fluid into said chambers. When passing through the rollers 52 and 53, the blades 56 sever the tubular structure at the transverse seals so as to divide the chain into individual fluid containing packages.

A special advantage of the invention is that the rollers, in sealing the package tubular structure acting through the standing column of liquid, make it possible to provide fluid package units without occluded air. That is, the package material is formed directly around the fluid without any possibility of undesirable air bubbles or the like, as such air bubbles usually have a very deleterious effect upon the contained commodity.

Another advantage of the invention is that only the interdigitated portions 17, 27 and 28 are heat sealed, the remainder of the compressed area of the package surrounding the chamber being cold pressed together thereby providing a safety expansion area whereby the layers of material may spread apart slightly permitting the fluid to expand when the chamber is being filled or when pressure is exerted on said chamber in use. The cold pressed area also permits the material to be easily torn for opening the package. Furthermore this cold pressure feature also permits the chamber 44 to be formed without wrinkling or tearing of the packaging material and allows the

material to be freely gathered so as to produce chambers of unusual and irregular shapes.

The present invention also contemplates offsetting the end edges of the webs of material from each other so that a package 60 such as shown in Figures 5 and 7 is obtained. In this package the margins are heat sealed and the edge 61 of the web 4 projects slightly beyond the edge 62 of the web 5 at the left of the package as shown in Figure 7, whereas the edge 63 of the web 5 projects slightly beyond the edge 64 of the web 4 at the right of the package. This permits the offset edges to be grasped by the fingers and the walls of the package readily separated for opening the package.

The modified form of package 65 shown in Figures 8 to 10, inclusive, may also be produced in accordance with the present invention. To produce this form of package, one of the webs, for instance, web 4, is wider than the web 5 so that its edges 66 extend beyond the edges 67 of the web 5 to facilitate grasping by the fingers. In this form, the package is heat sealed at spaced spots around the chamber 44, as indicated at 68, as well as at the edges.

In Figure 11 still another modified form of package 69 produced by the present invention is shown. In this particular form, the material of the package may be notched as indicated at 70 along one of the short edges of the package to initiate tearing of the package along a line passing through the cold pressed zone, whereby the package may be readily opened.

Still another modified form of package is shown in Figures 16 to 18, inclusive, in which the webs 4 and 5 are cold pressed together between the chamber 44 and the heat sealed margin 71 at one end thereof, as indicated at 72. Notches 73 are formed in opposite edges of the material adjacent one end to facilitate initial tearing of the material for opening.

In the modified form of the invention shown in Figures 12 to 14, inclusive, a machine of the reciprocating type is shown. Here the ribbons or webs 4 and 5 pass over idler pulleys 6 and 7 and are fed downwardly through the machine 45 and are fed downwardly through the machine by rotatable feed brushes 74 and 75 driven by any suitable means. The ribbons are sufficiently wide to pass on opposite sides of spaced pairs of pipes or tube 8 and 9 downwardly between and through crimping devices or blocks 76 and 77. Block 76 is carried by a reciprocating casting or bearing member 78 and block 77 by a similar reciprocating bearing member 79. The blocks are provided at their edges with vertically disposed crimping or corrugating projecting portions 80 and 81 and at their central portions with similar spaced crimping or corrugating portions 82 and 83. These crimping portions are adapted to mutually engage to forcibly interdigitate the edges of the ribbons as indicated at 84, and interdigitate the centers as indicated at 85 and 86. A vertically disposed movable perforating knife blade 87 is carried by the block 76 between the central crimping portions 82 and 83 and is spring pressed into engagement with a blade 87a in block 77 by means of plungers 88 and springs 89 mounted in the bearing member 78 for perforating the ribbons lengthwise. Nuts 90 adjust the tension of the springs on the blade. Both of the vertical crimping devices are provided with internal electrical heating elements 91 for heating the crimping portions.

From the vertical crimpers the ribbons pass 75 downwardly between and through devices for

crimping the material horizontally and for regulating or controlling the cross sectional area of the tubular structure and the amount of fluid commodity contained therein.

The horizontal crimping devices comprise a pair of opposed blocks 92 and 93 carried by the bearing members 78 and 79, respectively. Both blocks 92 and 93 are provided with a plurality of pairs of horizontally disposed projecting crimping or corrugating portions 94 and 95 with a space between the individual crimping portions of each pair. Three pairs of such crimping portions are shown. In the spaces between the individual portions of the pairs of crimping portions on block 92 are movable perforating knife blades 96 and on block 93 in such spaces are fixed blades 97. The movable blades are spring pressed into engagement with the fixed blades by means of plungers 98 and springs 99 mounted in the bearing member 78 for perforating the material horizontally. Nuts 100 are provided to adjust the tension of the springs on the blades. Internal electrical heating elements 101 are mounted in both of the blocks 92 and 93 for heating the horizontal crimping portions.

The regulating or controlling apparatus includes a bracket rail 102 fastened to the frame and provided with perforated bearing members 103. A rotatable shaft 104 extends between and through said bearing members with one of its ends projecting exteriorly of the frame and having a knurled knob 105 for actuating the same. Mounted on the shaft for reciprocation thereon toward and from each other are bearing sliders 106 and 107 formed with channel portions adapted to engage the bracket rail 102 to prevent relative rotative movement therebetween. Carried by and extending from the bearing sliders 106 and 107 to and between the blocks 92 and 93 are plates 108 and 109, respectively. The plates are formed with slots 110 to receive the projecting crimping portions of the blocks 92 and 93. On the shaft in the space between the bearing sliders 106 and 107 are nuts 111 and 113 slidable along the bracket rail 102, having threaded connections with right hand and left hand screws 112 and 114 respectively on the shaft 104 whereby upon turning of said shaft by the knob 105, the nuts will move toward and away from each other thereby moving the bearing sliders 106 and 107 respectively toward and away from each other along the shaft to decrease or increase the space between the plates 108 and 109 and thereby limit the space between the ribbons 4 and 5 of packaging material. Springs 115 are interposed between the bearing sliders 106 and 107 and the bracket portions 103 to normally urge said bearing sliders toward each other. Hooked members 116 are rigidly mounted on the bearing members 78 and 79 to engage the respective sliders 106 and 107 as the blocks 92 and 93 move apart, so as to move the plates 108 and 109 away from the ribbons 4 and 5 and permit free feeding thereof.

From the horizontal crimpers and perforating mechanism, the tubular structure next passes downwardly between and through forming or shaping dies in the form of blocks 117 and 118 carried by the reciprocating castings 78 and 79. The faces of these blocks are formed with crimping or corrugated surfaces or spaces for mutual complementary mechanical engagement as the blocks are moved into engagement with each other. The faces of the blocks are also formed with a plurality of spaced recesses 119, three of

such recesses being shown in each block to correspond in number with the three pairs of crimping portions of the horizontal crimpers. The crimping surfaces of these blocks are adapted to mutually engage to forcibly interdigitate the surfaces of the tubular structure as indicated at 120 and the recessed portions are adapted to coact to form chambers 121, each chamber being disposed centrally between the crimped edges of the structure as indicated in Fig. 15. The recesses may be of any desirable shape. In forming the chambers, the material above and below the recessed portion is gathered longitudinally of the webs as indicated at 122 in Figure 15.

At the bottom of the line of travel of the tubular structure, apparatus is provided for separating or cutting off the formed packages in single units. This apparatus comprises opposed blocks 123 and 124 carried by the bearing members 78 and 79 at their bottom ends. Both blocks are formed with grooved portions 125 in their faces. Block 123 is formed with shallow slots 126 above and below the grooved portions 125, and block 124 is provided with comparatively deep slots 127 in alignment with the slots 126 of block 123. Rubber covered metal blades 128 are supported in the slots 127 with their outer edges projecting slightly beyond the face of the block. These projecting edges of the blades are adapted to force the material of the tubular structure between the chambers 121 into the slots 126 and thereby stretch the material to the breaking point whereby the material is severed horizontally to form individual packages.

Any suitable mechanism may be used for reciprocating the bearing members 78 and 79 with their instrumentalities toward and from each other. I have shown a toggle control mechanism including a rod 129 mounted on and extending from the frame 130 of the machine. A sleeve 131 is slidable on this rod and is connected to a reciprocating driving element 132 by means of a cross pin 133. Element 132 is operatively connected to a suitable source of power. On opposite sides of the sleeve are link members 136, each link having one of its ends pivotally connected to the sleeve as indicated at 137 and pivotally connected to levers 138 as indicated at 139. Levers 138 are pivotally mounted at their centers on shafts 140 supported by the frame and are pivotally connected to shafts 141 carried by the bearing members 78 and 79. As will be understood, movement of the sleeve 131 will rock the levers 138 about their pivots and reciprocate the bearing members 78 and 79 with their associated parts toward and away from each other to effect their respective functions.

The operative face portions of the crimping or corrugating devices may have slanting or vertical or horizontal corrugations, or they may have pyramidal serrations or any other suitable crimping surface. In some cases said operative face portion may be smooth.

While I have described "cold pressing" certain zones of the packages, it may be desirable in many cases to "heat seal" the layers of packaging material in said zones.

While the machine illustrated in Figures 12 to 14, inclusive, is adapted to provide two rows of packages in chain formation and to form three individual packages in each row simultaneously, it will be understood that the machine can readily be adapted to make only one or more than two rows and only one or more than three packages at a time if desired.

The term "ductile material" as used hereinbefore and in the appended claims, means material which can be bent or pressed into and will retain a desired shape or contour and the term "ductile" does not exclude such resiliency, pliability or plasticity which is not inconsistent with the shape-holding qualities of the material.

Changes in details of construction may be resorted to and parts may be used without others within the spirit and scope of the invention.

What I claim is:

1. A machine of the character described comprising means for feeding strips of ductile material, opposed heated devices having projecting portions for heat sealing the strips along their edges, opposed heated devices having projecting portions for heat sealing said strips transversely at spaced intervals therealong and opposed die members having grooved portions for forming chambers in said strips between said transverse seals and having surfaces for cold pressing said strips between said chambers and the heated sealed portions.

2. A machine of the character defined in claim 1 characterized by means for cutting the strips into single packages.

3. A machine of the character described comprising means for feeding strips of ductile material, opposed heated rollers having projecting crimping portions for heat sealing the strips along their edges, opposed heated rollers having projecting portions for heat sealing said strips transversely at spaced intervals therealong and opposed rollers having grooved portions for forming chambers in said strips between said transverse seals and having surfaces for cold pressing said strips between said chambers and the heated sealed portions.

4. A machine of the character described in claim 3 characterized by means for cutting the strips into single packages.

5. A machine of the character described comprising means for feeding strips of ductile material, opposed heated rollers having projecting portions for heat sealing the strips along their edges, opposed heated rollers having projecting portions and having perforating blades for heat sealing said strips and for perforating said strips transversely at spaced intervals therealong, respectively, opposed rollers having grooved portions for forming chambers in said strips between said transverse seals and having surfaces for cold pressing said strips between said chambers and the heated sealed portions.

6. A machine of the character described comprising means for feeding strips of ductile material, opposed heated rollers having projecting portions for heat sealing the strips along their edges, means for transversely sealing said strips, means for forming chambers in said strips including rollers carrying floatingly mounted semi-circular die members having grooved portions and face portions bordering said grooved portions adapted to engage the strips and simultaneously form chambers and coldpress the strips between said chambers and the heat sealed portions, and means for severing said strips transversely into single units.

7. A machine of the character described comprising means for feeding opposed strips of ductile material, opposed rollers for crimping and heat sealing said strips along their edges for forming tubular structure, opposed rollers for simultaneously crimping, heat sealing and perforating said tubular structure horizontally,

means for feeding fluid into said tubular structure, opposed rollers for simultaneously shaping said tubular structure into chambers and for cold pressing the material around said chambers, and opposed rollers having cutting implements for severing the tubular structure horizontally.

8. A machine of the character described comprising means for feeding opposed strips of ductile material, opposed reciprocating blocks having vertically disposed portions for heat sealing said strips along their edges and centrally thereof for forming a plurality of spaced tubular structures, means for severing said spaced tubular structures longitudinally, means for feeding fluid into said tubular structures, means for heat sealing said tubular structures horizontally, means for forming chambers between said heat sealed portions and for cold pressing the material therebetween, and means for severing said tubular structures horizontally.

9. The process of forming a package consisting of the steps of feeding a pair of opposed strips of ductile material, heat sealing the edges of said strips to form a tubular structure, horizontally sealing said tubular structure at spaced intervals therealong and simultaneously forming a central chamber between the sealed portions of said structure and pressing the strips between said chamber and said sealed portions.

10. The process of forming a package consisting of the steps of feeding a pair of opposed strips of ductile material, heat sealing the edges of said strips to form a tubular structure, horizontally sealing said tubular structure at spaced intervals therealong, simultaneously forming a central chamber between the sealed portions of said structure and cold pressing the strips between said chamber and said sealed portions and severing the tubular structure horizontally.

11. The process of forming a package consisting of the steps of feeding a pair of opposed strips of ductile material, heat sealing the edges of said strips to form a tubular structure, simultaneously heat sealing and perforating said tubular structure horizontally, feeding fluid into said tubular structure, simultaneously forming a chamber centrally of said tubular structure and pressing the strips between said chamber and the sealed portions of the tubular structure, and severing the tubular structure horizontally.

12. The method of forming a package for fluent material which comprises feeding and sealing opposed layers of ductile web packaging material to form a tubular structure, feeding a fluent substance into said structure, externally applying pressure to the portion of said structure that contains said fluent substance and thereby pressing said layers into non-adhering contact with each other in zones which form and bound a compartment between said layers which is filled with said fluent substance, and sealing said layers tightly together in zones in spaced and encircling relation to said compartment.

13. The method of forming a package for fluent material which comprises feeding and sealing opposed layers of ductile web packaging material to form a tubular structure, feeding a fluent substance into said structure, externally applying pressure to the portion of said structure that contains said fluent substance and thereby pressing said layers into non-adhering contact with each other in zones which form and bound a compartment between said layers which is filled with said fluent substance, and sealing said layers

tightly together along the outer margins of the first-mentioned zones.

14. A packaging machine comprising means for continuously feeding opposed strips of ductile material, means for sealing said strips together in longitudinal zones to form a tubular structure, means for feeding fluent substance into said tubular structure, means for sealing said strips together transversely at longitudinally spaced zones to form packages each containing some of said fluent material, and means for pressing said strips into non-adherent contact in zones disposed inwardly of said sealed zones to form chambers and to force said fluent substance thereinto.

15. A packaging machine comprising means for continuously feeding opposed strips of ductile material, means for sealing said strips together in longitudinal zones to form a tubular structure, means for feeding fluent substance into said tubular structure, means for sealing said strips together transversely at longitudinally spaced zones to form packages each containing some of said fluent material, means for forming weakened

5 zones in said strips transversely through said transverse sealed zones between adjacent packages, and means for pressing said strips into non-adherent contact in zones disposed inwardly of said sealed zones to form chambers and to force said fluent substance thereinto whereby said strips may yield at said weakened zones to compensate for the movement of said ductile material during formation of said chambers.
